UNITED STATES PATENT OFFICE.

WILLIAM CARMAN, OF RICHMOND, VIRGINIA, ASSIGNEE OF ONE-HALF TO EDWARD C. JORGENSEN, OF BRATTLEBORO, VERMONT.

ELEVATOR-BRAKE.

1,068,105.

Specification of Letters Patent. Patented July 22, 1913.

Application filed March 29, 1913. Serial No. 757,551.

To all whom it may concern:

Be it known that I, WILLIAM CARMAN, a citizen of the United States, residing at Richmond, in the county of Henrico, State 5 of Virginia, have invented certain new and useful Improvements in Elevator-Brakes; and I do hereby declare the following to be a full, clear, and exact description of the invention, such as will enable others skilled 10 in the art to which it appertains to make and use the same.

This invention relates to improvements in elevator brakes, and has particular reference to a manually operated brake.

15 The subject-matter of this application has been divided out from my original application for improvements in elevator brakes, filed June 8, 1912, Serial Number 702,425.

The principal object of the invention is 20 to provide a simple device for checking the downward movement of an elevator when the rope breaks, and means for holding the elevator from further downward movement.

Other objects and advantages will be apparent from the following description and with particular reference to the accompanying drawings.

In the drawings: Figure 1 is a vertical section through an elevator and shaft showing my invention in inoperative position. Fig. 2 is a similar view showing the parts in operative position. Fig. 3 is a longitudinal sectional view on the line 3—3 of Fig. 2. Fig. 4 is an enlarged vertical sectional view on the line 4—4 of Fig. 3.

Referring particularly to the drawings, 10 represents the side guides of the elevator shaft. Formed in these guides, at equal distances apart, and the entire length of the 40 same are the stop shoulders or ledges 11 for engagement by a portion of the device to be described later. On each of the ledges is disposed a buffer plate 11' supported by the buffer springs 12' which absorb a great 45 amount of shock incident to the sudden engagement of the device to be described with the plate.

A car 12 is adapted to move up and down the shaft. Suspended beneath the floor of 50 the car, by means of the springs 13 is a

bumper plate 14. Mounted beneath the floor of the car on either side thereof, and adjacent the side guides 10, are the housings 15, in which are slidably disposed the loose pins 16, said pins being adapted for engagement on any of the ledges of the side guides. Also mounted within each of the housings, in rear of the pin 16 is a plunger 17, spring held inwardly by means of the spring 18. Slidable vertically through an opening in 60 the floor of the car is a foot plunger 19, and pivotally connected to the lower end of said plunger, at their inner ends, and at their other ends to the plungers 17 are the links 20. When the foot is pressed on the 65 foot plunger 19, the links 20 will force the plungers 17 outwardly, and force the pins 16 against the side guides, so that they will engage the plates 11' on the ledges 11. Upon releasing the foot from the plunger 70 19, the springs 18 will return the plungers to normal retracted position, leaving the pins partly resting on the plates 11' on the ledges 11 and partly within the housings. Thus the car is suspended until the cable 75 21 can be repaired. To release the pins 16 from the side guides, after the cable 21 has been repaired, and it is desired to start the car again, I use the means now to be described.

To the rear of each of the pins 16 I secure a cord or cable 22, both of said cables extending within the car and being connected together to a single cable 23, suitably suspended within the car. A handle 85 24 is secured to the said terminal so that a pull thereon will draw the cables 25 and move the pins 16 from the ledges 11, and into the housings 15. Thus when the rope breaks, the operator presses his foot on the 90 foot plunger 19 to throw the pins 16 outwardly to engage in the ledges on the side guides.

What is claimed is:

A brake device for elevators comprising 95 opposite side guides, having ledges, spring supported buffer plates on the ledges, housings on the opposite sides of the car, spring-retracted plungers in the housings, pins loosely mounted in the housings for pro- 100

jection therefrom and engagement with the buffers on the ledges of the side guides, a foot operated means connected to the plungers for movement of the plungers to project the pins from the housings, and hand operated means for withdrawing the pins from engagement with the side guides.

In testimony whereof, I affix my signature, in the presence of two witnesses.

WM. CARMAN.
